UNITED STATES PATENT OFFICE.

EUGÈNE SCHNEIDER, OF PARIS, FRANCE, ASSIGNOR TO SCHNEIDER & CIE, OF PARIS, FRANCE, A LIMITED JOINT-STOCK COMPANY OF FRANCE.

APPARATUS FOR LOADING GUNS.

1,326,789.

Specification of Letters Patent. Patented Dec. 30, 1919.

Original application filed February 14, 1918, Serial No. 217,193. Divided and this application filed March 31, 1919. Serial No. 286,482.

To all whom it may concern:

Be it known that I, EUGÈNE SCHNEIDER, a citizen of the Republic of France, and a resident of Paris, France, have invented a new and useful Improvement in Apparatus for Loading Guns, which invention is fully set forth in the following specification.

This invention has for its object to provide an improved apparatus for loading guns. In my pending application Sr. No. 217,193, filed Feb. 14, 1918, which eventuated in Patent No. 1,310,890, July 22, 1919, and of which the present application is a division, I have described and claimed the invention generically and one specific form thereof. In the present application there is shown and described a particular embodiment of the invention already shown and described in my said previous application 20 and generically but not specifically claimed therein.

The improved apparatus comprises, as usual, a loading carriage traveling in a framing located at the rear of the gun barrel and 25 having the shape of a scoop for receiving the gun charge (projectile and powder charge). In the same framing there is guided a rammer to which to-and-fro motion is imparted from the electric motor.

30 The invention consists of an apparatus that enables the actual movements of the rammer to produce automatically the necessary stopping of the driving motor at the ends of the forward (loading) stroke and 35 the rearward stroke of the rammer actuated by said motor, as well as reversal of the said motor when the rammer has arrived at the end of its forward stroke.

The apparatus comprises a clutch in which 40 one member is located on a shaft mounted in the fixed framing and ending at the controller of the electric motor. The other member of the clutch is located on the loading carriage and is connected to a shaft 45 mounted in the loading carriage which is operated by means of tappets by the rammer at the ends of its forward and rearward strokes.

In the particular embodiment herein described and claimed—

Figure 1 is a sectional side elevation showing the parts in their position in the beginning of the forward or loading stroke of the rammer;

Figs. 2 and 3 are vertical cross sections, 55 respectively, on the lines II—II and III—III of Fig. 1;

Figs. 4, 5 and 6 are longitudinal sections showing the parts in their position during the various stages of the loading operation; 60 and

Fig. 7 is a vertical cross section on the line VII—VII of Fig. 4.

Referring to these drawings in which like reference letters indicate corresponding parts of the structure, A is a fixed framing provided with rolling tracks *a* for the wheels *b* of the loading carriage B, and also, if desired, guideways *a'* for edges or wings *b'* of the said carriage. The carriage B is provided with a rack *B'*, Figs. 1 and 4, engaged by a pinion C fixed on a shaft *e* journaled in the fixed framing. By means of this pinion, the carriage may be moved into loading position shown in Fig. 1. 75

The rammer D is movable in the framing A and, for this purpose, it is provided with a pair of wheels *d*, Figs. 1 and 2, rolling on the guideways *a', a'* which are suitably prolonged to the rear. The rammer may also, if 80 desired, be provided with a pair of rollers at the forward end, not shown in the drawings. To-and-fro motion is imparted to the rammer by means of a pinion E meshing with a rack *D'* formed on the upper side of the 85 rammer. The shaft *e* on which the pinion E is fixed receives its motion from an electric motor *E'*, Fig. 2.

This apparatus produces the stoppage of the motor at the ends of the forward or 90 loading and rearward strokes of the rammer. It also effects automatically the reversal of the motor for the return stroke of the rammer.

In the lower part of the fixed member 95 A is journaled the shaft *i* having on its lower end the gear I; on the upper end of this shaft is the clutch-member J engaging the complementary clutch-member K on the lower end of the shaft *k* journaled in the 100 lower part of the carriage B. The gear I drives a gearing (not shown) that controls the switch of the motor *E'*. The detailed construction and operation of the clutch and gearing are shown and described in my 105 aforesaid application and patent. On the shaft *k* is fixed a bevel pinion L which constitutes one of the parts of the gear actuated

by the rammer D when the latter has arrived at one of its end positions. This gear may comprise, as shown, a toothed arc M' on an axle m journaled in the carriage B. The 5 end M² of the rocking beam farthest from the arc M' is connected by a link N to a lever O fixed on an axle o journaled in the carriage B. The hub of this lever O has two upwardly projecting fingers P and Q adapted 10 respectively to engage a forward stop R, Figs. 4 and 5, and a rear stop S provided on the under side of the rammer D.

At the end of the forward stroke of the rammer the impact between the rear stop 15 S and the finger Q will produce, by the tilting of the finger Q and the depression of the latter beneath the stop, a rocking movement of the lever O which will have the result of actuating, through the gear M— 20 N—M', the pinion L in such a manner as to move the clutch member K into engagement with the clutch member J. And, inversely, the impact between the forward stop R and the finger P at the end of the rearward 25 stroke will cause the lever O to rock in the reverse direction and move the clutch member K back into its initial position.

All of these parts thus far described combine and coöperate substantially in a manner set forth in my aforesaid application and patent.

D² is a scoop secured to the forward end of the rammer D, said scoop being designed to receive the powder charge V', the projectile V resting on the carriage proper immediately in front of said scoop but in a position to be engaged thereby.

The rammer includes a piston D³ provided with a spring catch d³ adapted to engage a recess l formed in the breech of the gun. The piston D³ is connected by a suitable piston-rod with an enlarged piston-like member D⁵ telescoping with the rammer D.

45 At the beginning of the ramming operation, the parts are in the position shown in Fig. 1. The projectile V bears with its rear end against the front edge of the rammer scoop D² and the powder charges V' are situated in the scoop, the rearmost powder charge bearing against the piston D³, all as clearly illustrated in Fig. 1.

In the ramming stroke, the entire gun charge is pushed into the gun chamber into 55 which the scoop D² enters temporarily, Fig. 4, the catch d³ engaging at the end of the ramming stroke in the recess l, as clearly shown in said Fig. 4. In the rearward stroke the scoop D² slides away from beneath the powder charges V', which charges 60 are retained in the gun chamber by the pis-

ton D³, as illustrated in Fig. 5, the spring catch holding the piston against any tendency to move backward with the scoop.

When the parts have come into the position shown in Fig. 5, the guide sleeve D⁴ of the piston rod will contact at its rear end d⁴ with a large piston-like member D⁵ of the piston rod and will thus move the piston D³ back with it in the rearward stroke 7 of the rammer, the spring catch yielding under the power applied and releasing the piston.

When this rearward stroke is completed, the parts will be in the position shown in Fig. 6 and it will only be required to push back the piston D³, by hand or otherwise, to return it into the initial position shown in Fig. 1.

By the construction thus described, it will be perceived that it is rendered feasible at a single stroke of the rammer to place the projectile and the powder charges in the gun, the reverse stroke of the rammer entirely removing the latter from the breech and into position for loading another charge.

What is claimed is:—

In an apparatus for loading guns, the combination with a loading carriage, a fixed framing in which said carriage can be moved out of the way during firing and in which said carriage travels, a rammer having a to-and-fro motion in said framing, and a motor for operating said rammer, of two complementary clutch members one of which is located on the loading carriage and the other on said fixed framing, a first gear whereof said clutch member on the framing forms a part, said first gear being adapted to drive a controlling device for starting and stopping said motor, a second gear whereof said clutch member located on said carriage forms a part and actuated by said rammer in its to-and-fro movements whereby the to-and-fro movements of said rammer determine automatically the starting and stopping of the latter, a scoop for receiving the powder charges located at the front of said rammer for ramming a projectile and its powder charges in a single operation, a piston for ramming the powder charges guided in said scoop, a catch adapted to engage the gun breech at the end of the ramming stroke, and means whereby said piston is moved back by said rammer on the rear stroke of the latter after it has pushed the powder charges out of said scoop into the gun chamber.

In testimony whereof I have signed this specification.

EUGÈNE SCHNEIDER.
